CLAIM

The ornamental design for sunglasses towel clip, as shown.

DESCRIPTION

FIG. 1 is a rear perspective view of sunglasses towel clip showing my new design;

FIG. 2 is a front elevational view thereof;

FIG. 3 is a bottom elevational view thereof in an open position;

FIG. 4 is the bottom elevational view thereof in a closed position; and,

FIG. 5 is a left side elevational view thereof.

The broken lines depict portions of the article that form no part of the claimed design.

1 Claim, 5 Drawing SheetsFIG. 1

FIG. 2

FIG. 3

FIG. 4

FIG. 5

UNITED STATES PATENT AND TRADEMARK OFFICE
CERTIFICATE OF CORRECTION

PATENT NO. : D752,967 S
APPLICATION NO. : 29/473964
DATED : April 5, 2016
INVENTOR(S) : Harvey A. Katz
